[57] CLAIM

The ornamental design for a scribing rule guide or similar article, as shown and described.

DESCRIPTION

FIG. 1 is a perspective view of a scribing rule guide, showing my new design;

FIG. 2 is a top plan view thereof;

FIG. 3 is a right side elevational view thereof;

FIG. 4 is a bottom plan view thereof;

FIG. 5 is an inverted left side elevational view thereof;

FIG. 6 is a front elevational view thereof; and

FIG. 7 is a transverse sectional view taken on the line 7—7 of FIG. 3.
